UNITED STATES PATENT OFFICE.

CHARLES H. BRADLEY, OF PITTSBURG, PENNSYLVANIA.

DESIGN FOR A HEATING-STOVE.

SPECIFICATION forming part of Design No. 16,519, dated February 16, 1886.

Application filed September 3, 1885. Serial No. 176,120. Term of patent 7 years.

To all whom it may concern:

Be it known that I, CHARLES H. BRADLEY, a citizen of the United States, residing at Pittsburg, in the county of Allegheny and State of Pennsylvania, have invented and produced a new and original Design for Stoves, of which the following is a specification, reference being had to the accompanying engraving, forming part thereof.

10 The leading features of my design are panels with interior figures and figures arranged on the sides of upper and lower air-inlets.

The figure is a perspective view of the stove.

A is the stove, whose front is formed of panels a a' a'' a''' . The panels a have a raised surface with parallel sides and concaved corners, on which surface is a head, which forms a figure consisting of a main body, b , and subsidiary ends b' . The whole figure is formed of inwardly-curved lines, the sides being of several times greater length than the ends. Said body b has its sides formed of a single line each, while its ends are each formed by two convergent lines greatly less in length than either of the sides. The end portions, b' , are approximately diamond-shaped, with concaved outline, the two sides nearest the main body b being formed by the crossing and continuation of the end lines of the latter. The panels a' are similar to a , except that the parallel-sided surface is sunken instead of being raised. The panels a'' are similar to panels a , except

that the sides of the main body b of the raised bead-work are connected by a bar. The panels a' , being at the upper corners of the stove-front, are smaller than those already described, and the beaded figure is set horizontally instead of vertically. There are two panels a'' , situated as described, two panels a''' , forming the doors of the stove, two panels a'' , situated on either side of panels a' , and four panels a'' , situated beneath panel a''' . The blower C has two upper draft-orifices, and outside of same are two figures, c , (one at each end,) consisting of a circular bead, the top and bottom of which are connected by short stems with four-pointed-star flowers. In the lower curved portion of the blower are four draft-orifices, between and outside of which are five figures, c' , consisting of five-pointed-star-shaped flowers, each flower having a pendent stem provided with two leaves.

I claim—

1. In a design for a stove, the front thereof, consisting of panels a a' a'' a''' and the interior figures, b b' , as shown and described.
2. In a design for a stove, the figures c c' , respectively, on the sides of the upper and lower orifices, as shown and described.

CHAS. H. BRADLEY.
